Inventor:

Christian Pedersen

UNITED STATES PATENT OFFICE.

CHRISTIAN PEDERSEN, OF UGLEDIGE, NEAR ALLERSLEV, DENMARK.

SUSPENSION DEVICE FOR MAPS AND THE LIKE.

Application filed March 26, 1927, Serial No. 178,787, and in Denmark March 29, 1926.

This invention relates to a device for suspending maps and the like and is intended chiefly for use in schools. The maps must, however, have wooden rods at the lower rim, as is generally the case with maps for schools. The device may be affixed to a board that is to be attached to the respective wall, or may be secured directly to that wall. It can be used in connection with 10 maps of several sizes, and can wind up the map automatically into its position of rest in which the map forms a cylindrical body. The map can be opened to any desired extent and can then be secured in the respective position. In order to release the checked map it is sufficient to pull it downwards a little, as is more fully described hereinafter.

The invention is illustrated diagrammatically and by way of example on the accompanying drawing on which Figure 1 is a front-view of the device, Figure 2 a cross-section through one (the lefthand in Fig. 1) of two clamping bows, together with a 25 front view of the appertaining wooden rod, this figure being drawn to an enlarged scale, and Figure 3 is a cross-section in line I—I of Fig. 1, also drawn to an enlarged scale.

On the drawing, 1 denotes a board having eyes 2 by which it can be suspended from a wall or the like. On the lefthand end of the board 1 is a casing 4 held by bows 3, and within this casing is a spring-actuated wheel-work of the kind used in 35 connection with roller-blinds for winding them up automatically. I have abstained from showing this winding device in detail because it is known and does not form a part of this invention. A pivot-like shaft 5 projects forth from the casing 4, and to it is affixed a clamping bow 6 provided with a clamping screw 7 that extends through the two arms 9 of the bow and is provided with a wing-nut 8. The arms 9 are so curved 40 (Fig. 2) that they can hold securely the rod 10 which is connected with the upper rim of the map 11. A similar clamping member 12 as that just described is provided at the right hand end of the board 1 and has a

50 pivot 13 supported in a bracket 14 affixed to a slide 15 coupled with the board 1 by grooves and feathers 16 (Fig. 3) forming parts of a ledge 17 projecting forth forwardly from the board 1. The device can, thus, be adjusted for maps of various lengths 55 and the slide 17 can be secured in every position by a screw 18. The right hand clamping bow is constructed exactly as that on the left. 19 denotes its clamping screw 60 and 20 the wing-nut, on the same. 60

I claim:

1. A suspension device for maps and the like, comprising, in combination, two oppositely located clamping bows adapted to receive and hold fast the rod attached to 65 the upper rim of the map, one of said bows being adjustable with respect to the other bow according to the length of said rod, and an automatic winding and checking device connected with the other clamping bow, substantially as described. 70

2. A suspension device for maps and the like, comprising, in combination, two oppositely located clamping bows adapted to receive and hold fast the rod attached to 75 the upper rim of the map, a slide to which one of said bows is attached and which can be adjusted with respect to the other bow, an automatic winding and checking device connected with this other bow, and a board 80 to which said winding and checking device is attached and upon which said slide can be shifted, substantially as described.

3. A suspension device for maps and the like, comprising, in combination, two oppositely located clamping bows adapted to receive and hold fast the rod attached to the upper rim of the map, one of said bows being adjustable with respect to the other bow according to the length of said rod, and an 90 automatic winding and checking device connected with the other clamping bow, the arms of both clamping bows being so curved as to be adapted to hold fast securely the round map bar, substantially as described. 95

In testimony whereof I affix my signature.

CHRISTIAN PEDERSEN.
